UNITED STATES PATENT OFFICE.

RICHARD F. DOWNEY, OF MILWAUKEE, WISCONSIN, ASSIGNOR OF ONE-HALF TO
WILLIAM J. CARY, OF MILWAUKEE, WISCONSIN.

AMUSEMENT DEVICE.

Application filed September 16, 1921. Serial No. 501,055.

To all whom it may concern:

Be it known that I, RICHARD F. DOWNEY, a citizen of the United States, and resident of Milwaukee, in the county of Milwaukee, 5 and State of Wisconsin, have invented certain new and useful Improvements in Amusement Devices; and I do hereby declare that the following is a full, clear, and exact description thereof.

10 My invention relates to a new and improved amusement device which is in the nature of a sweep which is pivoted to swing or rotate about a central standard and is adapted to carry a child supporting 15 device at its outer end.

The general object of the invention is to provide a device of this type which will have a number of adjustments by which it may be readily adapted for amusing babies 20 and small children in a variety of different ways.

A further object of the invention is to provide a device of inexpensive construction which includes a mechanically driven 25 sweep provided with means for supporting a small child and carrying him after the manner of a merry-go-round.

With the above and other objects in view which will be apparent from the following 30 description the device consists of certain structural details which are shown in the accompanying drawings and set forth in the claims hereunto appended.

In the drawings:—

35 Figure 1 is a side elevation of my invention.

Figure 2 is a plan view thereof.

Figure 3 is a vertical sectional view of 40 the central standard which is a part of the invention, and

Figures 4 to 9 inclusive are detailed views showing various parts of the invention.

Referring by reference characters to the drawings the invention comprises a central 45 hollow standard 1 secured to a suitable base 2 and provided at its upper end with a bearing member 3 which carries ball bearings 4 on which a head 5 is rotatably supported. The head 5 is provided with suitable trunnions 6 on which a sweep 7 is pivoted. The sweep has preferably a split bearing 8 at its outer end which is adjustable by means of a threaded bolt 9 and in which any suitable training or amusement device may be detachably secured.

The device which I have shown secured in the bearing 8 by way of illustration consists of a bracket 10 which carries a support 11 consisting of a seat 12 having a back 13 and the sides 14. It will 60 be readily seen that a baby may be placed on the seat 12 and may be tied in if necessary and the sweep may be rotated about the central standard by means hereinafter described.

For the purpose of supporting the outer end of the sweep and the weight of the seat and child carried thereby, a counter-balancing spring is provided which is secured at one end to a pin 16 and at its other end 65

to an L shaped arm 17 secured to the head 5. For the purpose of adjusting the effective strength of the counter balance to correspond to the weight carried at the end 70 of the sweep, the pin 16 is adjustably mounted in the longitudinal slot 18 and a plurality of notches 19 are provided in the arm 17.

A spring motor is provided for rotating the head and the sweep carried thereby when desired. This motor includes 75 a coil spring 20 secured at one end to a shaft 21 which is journaled centrally of the standard and extends upwardly through the head 5, the other end of the spring 20 being secured as shown at 22 to a disc 23 80 journaled on the shaft 21 and held against longitudinal movement thereon by a pin 24. A dog 25 is pivotally mounted on the standard 1 and adapted to engage the disc 23 to prevent its rotation with respect to 85 the standard when the spring motor is used.

This dog is provided with a handle 26 which in the position shown in Figures 4 and 5 holds the pawl in engagement with the disc by gravity. When the handle 26 90 is moved to the left as shown in Figure 1 the disc 23 is released and the spring motor is rendered inoperative for a purpose hereinafter described.

A handle 27 is secured to the upper end of the shaft 21 for the purpose of winding up the spring and a spring latch 28 is provided in the head 5 95 for locking the handle 27 and shaft 21 against a return movement.

When the pawl 25 has been thrown into 105 engagement with the disc 23 and the spring wound up the torsional force of the latter will be exerted through the latch 28 and head 5 to rotate the latter and the sweep which carries the training support 11 at its 110

outer end. In order to prevent the sweep from revolving too rapidly a device in the nature of a governor is provided which consists of a weight 29 supported by a flexible 5 cord 30 from the outer end of the arm 17. A post 31 is secured to the base a short distance outside of the end of the arm and as the sweep revolves the centrifugal force will carry the weight 29 outside of the post and 10 the cord will be wrapped around the post thus checking the movement of the sweep. In the normal operation of the sweep therefore, under influence of the spring motor the movement thereof will be checked at 15 each revolution thus providing a novel and interesting amusement for very young children. A scale 32 may be provided on the sweep which in connection with a pointer 33 secured to the head 5 may indicate the 20 weight of the child carried by the support 11, the scale being calibrated so as to indicate the correct weight with the spring 15 in a predetermined position. The device when used in connection with the spring motor is 25 primarily an amusement device. When it is desired to use the device to train the child to walk the motor is disconnected by moving the arm 26 to the left as shown in Figure 1 and any suitable guiding device may be substituted for the seat carried by the outer end 30 of the sweep. The sweep will then be freely revoluble about the shaft 21. When the device is used in this manner it is desirable to provide means for preventing a backward movement which might cause the child to 35 fall backward. For this purpose the bearing member 3 may be provided with a flange which forms an annular groove 34, the bottom of the groove being provided with 40 ratchet teeth 35. A ratchet arm 36 is pivotally connected to the sweep 7 and provided at its outer end with a tooth 37 at each side thereof. The arm 36 is loosely pivoted so as to be swung into a position at either side 45 of the standard where one of the teeth 37 may engage with the teeth 35 permitting movement of the sweep in one direction but preventing its movement in the opposite direction.

50 I have also found that, if the hollow standard within which the spring motor is located be filled with grease of rather stiff consistency, the pendulum governor may be dispensed with. The slowly yielding resistance 55 of the grease will permit the spring to gradually unwind and yet if it is of the proper amount and consistency, it will retard the movement sufficiently for practical purposes.

60 From the foregoing description it will be seen that I have provided a device which is comparatively inexpensive and yet may be used for amusing and training very young children in a great variety of ways. While

I have shown and described a number of 65 ways in which it may be adjusted and a number of uses to which it is adapted, it will be readily seen that other ways of using it may be devised and other attachments may be provided for it. The invention therefore is not limited to the structural details and uses set forth but comprises all equivalents which fall within the scope of the appended claims.

I claim as my invention:—

1. A device of the character described comprising a hollow standard, a shaft journaled centrally thereof and projecting from its upper end, a disc journaled on the shaft within the standard, a coil spring surrounding the shaft and having one end secured thereto, the other end of the spring being secured to the disc, means for locking the disc to the standard, means for rotating the shaft to wind up the spring when the disc is so locked, a sweep rotatably supported by the standard and journaled to the upper end of said shaft, and a ratchet device for locking the sweep to the shaft when the latter is rotated under influence of the spring.

2. A device of the character described, comprising a standard, a head rotatably supported thereon, a sweep pivotally connected to the head and having a supporting device secured to its outer end, a spring motor, means for operatively connecting the motor to the head to rotate the same, an arm depending and extending outwardly from the head on the opposite side of its axis from said supporting device, a counter balancing spring adjustably connecting the arm with the sweep, a post mounted outside the path of said arm and a flexibly supported weight carried by the arm and cooperating with said post to check the travel of the sweep intermittently at each revolution.

3. A device of the character described comprising a hollow standard, a head rotatably mounted at the upper end thereof, a shaft extending through the head and through the standard longitudinally thereof, a coil spring surrounding the shaft and having one end secured thereto, a disc journaled on said shaft and having the other end of the spring secured thereto, means for optionally locking said disc to the standard, means for rotating the shaft in one direction with respect to the head to wind up the spring, means for preventing a reverse rotation thereof, a sweep carried by the head and means for securing a support to the outer end of the sweep.

In testimony that I claim the foregoing I have hereunto set my hand at Milwaukee, in the county of Milwaukee, and State of Wisconsin.

RICHARD F. DOWNEY.
